UNITED STATES PATENT OFFICE.

AUGUST W. STEINKE, OF CHICAGO, ILLINOIS, ASSIGNOR, BY MESNE ASSIGNMENTS, TO
AMERICAN ELECTRIC COMPANY, OF CHICAGO, ILLINOIS, A CORPORATION OF MAINE.

SUPERVISORY SYSTEM.

Application filed June 20, 1925. Serial No. 38,488.

This invention relates in general to supervisory provisions in telephone systems.

Specifically the invention relates to an improved universal cord circuit which automatically adapts itself to the type of line with which it is being used, and which arranges its supervisory circuits so that a flashing supervisory signal is given in connection with a magneto line and a steady 10 supervisory signal is given in connection with a common battery line.

In a well known magneto line telephone system employing line lamps to call the operator's attention to a calling line, a ring-up relay is energized by the substation generator to close the circuits to the line lamp. Supervision in the cord circuit is obtained by a similar means, that is, a ring-up relay is energized by the substation 20 generator to close the circuit to the supervisory lamp signals. In such a system, after the subscriber has once operated his generator and locked up the ring-up relay in the cord circuit, he has no means of re-signaling the operator should she fail to notice the first signal. It is therefore imperative to good service that this supervisory signal be displayed as conspicuously as possible.

30 In a common battery system, the subscriber resignals the operator by momentarily replacing his receiver, which operates cord circuit relays in the well known manner to display the supervisory lamps. Should the operator fail to give attention to the cord circuit, the common battery subscriber may press his demands by jiggling the receiver hook which causes the supervisory light to be flashed. It is quite apparent 40 that the common battery subscriber is better able to obtain recall and disconnect service from the operator, than the magneto subscriber is, and that, therefore, he does not really need flashing supervisory signals.

45 It is frequently necessary in the interests of good service to indiscriminately inter-splice common battery and magneto lines on the switchboard before the operator, and it is necessary to provide this operator with 50 means for answering calls from and extending calls to either type of line with a minimum of effort. In such installation it is common practice to have the signaling control for magneto lines manually operated by

the operator, and to have the signaling of 55 common battery lines fully automatic with instantaneous ring-cutoff when the called party answers.

Accordingly, an object of my invention is to provide an improved universal cord circuit 60 which adapts itself automatically to the type of line with which it is being used, and which adapts itself to render flashing or steady supervisory signals, depending upon whether it is being used with a magneto or 65 with a common battery line. Further objects of my invention not specifically mentioned here will be apparent from the detailed description and claims which follow.

The drawings comprising Figs. 1 and 2, 70 when placed with Fig. 2 to the top of Fig. 1 with corresponding lines in alignment, show sufficient equipment to enable a full understanding of my invention.

In Fig. 1 is shown a universal cord circuit 75 designed in accordance with the objects of my invention. This cord circuit comprises the usual listening key L, ring back key RB, repeating coil I, and cord circuit supervisory signals AS and CS, with the 80 associated generators, ringing interrupters, and supervisory pilots.

Figure 2, shows four subscriber stations A¹ to A⁴, inclusive, terminating at the jacks of a manual switchboard, with the associated 85 line and cutoff relays individual to each line. It should be noted that the subscriber stations, A¹ and A³ are magneto stations employing a hand generator to signal the operator, and having a local battery transmitter feed circuit. The subscriber's lines A² and A⁴ are equipped for common battery 90 service.

In order to simplify the drawings, I have shown a plurality of batteries, whereas in 95 an exchange installation there would be one battery preferably with the positive pole grounded.

Having described my invention in general, I will now proceed with a detailed description of its operation. Assuming that the subscriber at station A¹ desires to call the station A³, he will operate his hand generator to energize his line relay LR¹, over a circuit, traceable from the lower terminal of the 100 hand generator, over the line conductor T¹, through the upper cutoff relay springs to the winding of the line relay LR¹, through 105

the lower cutoff relay springs, over the line conductor R^1 , to the other side of the generator. Relay LR^1 upon energizing closes a circuit from ground, through its make contact, through the line lamp LL^1 , to battery. The operator upon seeing the line lamp lighted picks up the plug AP , for example, and inserts it into the answering jack AJ^1 to answer the call.

- 10 Insertion of the answering plug AP into the jack AJ^1 closes a circuit which is traceable from ground, through the two windings of the cutoff relay CO^1 in series, through the sleeve terminal of the jack AJ^1 and the plug AP^1 , over the sleeve conductor S , and through the winding of the marginal relay 102 to grounded battery. The cutoff relay CO^1 energizes over this circuit, breaks the previously traced circuit for the line relay 20 LR^1 , and restores the armature of relay LR^1 to normal by means of a mechanical interlocking device, thereby extinguishing the line lamp LL^1 . In the cord circuit, relay 102, being marginal, will not energize in series 25 with the cutoff relay, when the two windings of the latter are connected serially.

- The operator now throws her listening key L to close the contacts 162, 164 and 167, and the subscriber removes the receiver from 30 the switchhook, thereby adapting the equipment to receive the conversational orders. The voice currents from the substation A^1 travel over the line conductor R^1 , through the jack and plug over the plug, conductor 35 R , through the key contacts 161 and its break contact, through the winding 111 of the repeating coil I , through the condenser C , through winding 110 of the repeating coil, through key contacts 160, the tip conductor 40 T , through the plug and jack, through the tip line conductor T^1 , thence through the telephone in the well known manner. Currents induced in the windings 112 and 113 of the repeating coil are conducted to the operator's 45 head set over spring 162 and its make contact, and over the spring contact 164. The operator receives the number of the wanted station and inserts the calling plug CP into the calling jack CJ^1 , thereby extending a 50 connection to the called party A^2 . Insertion of the plug CP in the jack CJ^1 completes a circuit from ground, through the two windings of the cutoff relay CO^2 in series, through the sleeve connection of the jack 55 and plug, the sleeve conductor S' , through the winding of relay 105 to battery. The cutoff relay CO^2 energizes over this circuit and disconnects the line relay LR^2 , thereby preparing the called line for the subsequent 60 application of ringing current. Relay 105, being marginal will not energize in series with the cutoff relay, when the two windings thereof are connected serially. The operator then reoperates her listening key L to open 65 the springs 162, 164 and 167 and to close

the springs 165 and 166 thereby projecting ringing current from the generator G , through the spring 166 and its make contact, the ring conductor R' and ring of the plug CP and the jack CJ^2 , over the ring line conductor R^2 , through the bells of the called station A^2 , to the tip conductor T^2 , through the tip of the jack CJ^2 and the plug CP , tip conductor T' , through the spring 165 and its make contact to ground. The called 70 party answers his signal now and conversation takes place in the well known manner.

When the subscribers have completed their conversation they replace their receivers and operate their generators to notify the operator that their connection can be taken down. Operation of the hand generator at substation A^1 projects current out over the talking conductor T to the winding 110 of the repeating coil I , thence through the break 75 contact of spring 121, through the winding of relay 101, to the winding 111 of the repeating coil, ring conductor R , and thence over the previously traced circuit back to the generator. The relay 101 is energized 80 in this circuit and locked in an energized position by means of the well known ring-up lock with which it is equipped. Operation of relay 101 closes a circuit from ground, through the answering supervisory lamp AS , 85 springs 126, through the winding of relay 116 to battery. The relay 116 is operated over this circuit, while the signal AS does not light in series with relay 116. The latter, upon operating, closes the spring 135, 90 establishing an obvious circuit to relay 115 and flashing pilot FP . Relay 115 energizes, at spring 130 supplies direct battery to the signal AS and shunts out the relay 116, which deenergizes after an interval and 95 opens the circuit of relay 115. The signal AS being connected to direct battery while relay 115 is energized, will light. Relay 115 deenergizes after an interval to again permit 100 116 to energize. This interaction of relays 115 and 116 causes the flashing pilot FP and the answering supervisory lamp AS to flicker in the well known manner.

Operation of the hand generator at station A^2 projects signaling current over the line conductor T^1 to the winding 112 of the repeating coil I and then through the break contact of spring 131, through the winding of relay 106, through the winding 113 of the repeating coil, and thence over the previously traced circuit back to the generator. Relay 106 energizes over this circuit and locks up by means of the well known mechanical lockup device previously referred to. Operation of relay 106 closes a circuit from 115 ground, the calling supervisory lamp CS , springs 140, through springs 136, and thence through the relay 116 over the path identical with that already traced. The calling 120 supervisory lamp CS is flashed in the manner 125 130

similar to that described for the answering supervisory lamp AS. The operator upon observing the flashing signal operates her listening key to close springs 162, 164 and 167, closing a circuit from ground, spring 167 and its make contact, thence through two parallel paths, the one through resistance 119 through spring 132 and its break contact, through the lower winding of relay 104 to battery, and the other through resistance 109, spring 122 and its break contact, through the lower winding of relay 103 to battery. Relays 103 and 104 energize over the circuits and, by means of the mechanical interlocking device, by means of which they are connected to relays 101 and 106, respectively, unlock the latter relays and restore them to normal. This operation opens the circuit of answering supervisory lamp AS at spring 126, and of the calling supervisory lamp CS at spring 136, extinguishing them. The operator, when operating her listening key L, connects her headset to the cord circuit and, before taking down the connection, inquires for further instruction from the subscribers. If no further instruction is received she removes the plugs AP and CP and restores the key L to normal, restoring all energized relays and putting the equipment in readiness for another call.

When a subscriber at A¹ desires to call a subscriber at A⁴, the operation is identical up to the point where the operator inserts the calling plug CP into the calling jack. Having received the instructions to connect to the line A⁴ the operator inserts the plug CP into the calling jack CJ⁴, closing a circuit from ground, through the two windings of the cutoff relay CO⁴ in parallel, through the sleeve connection of the jack CJ⁴ and the plug CP through the sleeve conductor S', through the winding of relay 105 to grounded battery. Relays CO⁴ and 105 both energize over the circuit, relay 105 being marginally adjusted to energize in series with the two windings of the cutoff relays when they are connected in parallel. Relay CO⁴, upon energizing, disconnects the line relay LR⁴ from the line conductors C⁴ and R⁴, thereby preparing that line for the application of ringing current. In the cord circuit relay 105 upon energizing at springs 131 and 132 prepares the battery feed circuit for station A⁴ by connecting the relay 104 across the condenser C'. At spring 133, relay 105 prepares the circuit for the ringing control relay 108, and at spring 134 closes the circuit from ground through calling supervisory lamp CS, springs 140, springs 124, springs 134 to battery, lighting the calling supervisory lamp CS. The operator noting that the calling supervisory lamp CS is operated knows that she is calling a common battery line and therefore operates the ringing key RK, causing a circuit from ground

through springs 168, through the winding of relay 108, through springs 178 and 133 to battery, energizing the relay 108. Relay 108 upon energizing locks itself through springs 139, 137, 127, spring 120 and its break contact to ground; at springs 138 and springs 150 prepares the circuit for the application of ringing current to the called line; and at spring 140 breaks the previously described circuit to the calling supervisory CS, to extinguish that lamp. Ringing current is now projected out on the called line over a circuit traceable from grounded battery to the ringing generator G through spring 151 and its break contact, through the winding of relay 107 and the resistance 107' in parallel, through spring 138 and its make contact, spring 165 and its break contact, over the tip conductor T', the tip of the plug CP, the jack CJ⁴, line conductor T⁴, through the hookswitch, bells and condenser of the called substation A⁴, to ring conductor R⁴, through the ring of jack CJ⁴ and plug CP, over the ring conductor R', through the spring 166 and its break contact, through spring 150 and its make contact to ground. The ringing interrupter R' revolves, and in due course of time closes the obvious circuit for the relay 117, which energizes and breaks the above ringing current at springs 151, supplying direct battery to the ringing circuit. The bells at station A⁴ are thereby intermittently rung until the called party answers. When the called party removes the receiver from the switchhook, a direct current bridge is formed across the line by substituting the receiver and the transmitter for the bells and the condenser. If this occurs during a ringing period, direct current is projected from the battery through the generator, and thence over the previously traced circuit to ground at spring 150; and if this occurs during a silent period, battery is projected from spring 151 and is make contact, thence over the previously traced circuit to ground at spring 150. In either case relay 107 energizes in this direct current circuit, and at spring 137 breaks the previously described locking circuit of ringing control relay 108, allowing that relay to restore. Relay 108 at spring 138 and its break contact, and spring 150 and its break contact, completes a circuit from the substation over the previously described circuit, to spring 138 and its break contact, through winding 112 of the repeating coil I, through spring 131 and its make contact, through the upper winding of relay 104 to ground, and through the other branch to spring 150 and its break contact, through the winding 113 of the repeating coil I, through the spring 132 and its make contact, through the lower winding of relay 104 to grounded battery. Relay 104 energizes over this circuit in series with the

transmitter and receiver of the station A⁴, and at spring 124 interrupts a point in the circuit of calling supervisory lamp CS to prevent that lamp from lighting as long as the receiver at station A⁴ remains off the hook. At spring 178 relay 104 interrupts the circuit of ringing control relay 108 to prevent the reenergizing of that relay should the key 163 be accidentally depressed. The 10 parties A¹ and A⁴ may now converse, the former receiving battery supply to the transmitter coming from the local battery over the previously described circuit, and the latter receiving its transmitter battery supply 15 through the windings of relay 104.

When the conversation is completed station A¹ rings off as before to display the flashing supervisory lamp AS. Station A⁴ replaces his receiver breaking the circuit to 20 relay 104, which falls back and at spring 124 closes the circuit to calling supervisory lamp CS, causing that supervisory lamp to be lighted. The operator, noting the signals, supervises the call and removes the plugs as 25 described previously.

In case the subscriber at station A² desires to make a call, he removes his receiver from the switchhook, closing the circuit to 30 the line relay LR², which energizes and lights the line lamp LL². The operator, noting the lamp, inserts the plug AP into the jack AJ², closing a circuit from ground through the two windings of the relay CO² in parallel, to the sleeve of jack AJ² and plug AP, 35 through the winding of relay 102 to battery. Relays CO² and 102 energize over this circuit, the former opening the circuit of line relay LR² which falls back and extinguishes the line lamp LL². In the cord circuit, relay 102, upon energizing, at springs 121 and 122 connects the relay 103 across the line circuit in series with the windings 110 and 40 111 of the repeating coil I. Relay 103 energizes, at spring 125 opens the circuit of the answering supervisory lamp AS, and at spring 124 prepares a point in the locking circuit of the ringing control relay 108. The operator operates her listening key to ascertain the number of the wanted party, which 45 may be either A³ or A⁴. The calling operation is identical with the previous description. In the event that the wanted party is station A⁴, the operator rings this station by locking up the relay 108 over a circuit traceable by way of springs 139, 137, 124, and 50 120, and its make contact, to ground. If the wanted party answers, the circuit is interrupted at spring 137 when the relay 107 energizes. If, however, the called party does 55 not answer promptly and the calling party replaces his receiver abandoning the call, the locking circuit of relay 108 is broken at spring 124 when the relay 103 deenergizes. Relay 108 falls back and completes the 60 circuit of calling supervisory lamp CS light-

ing this signal steadily, and the circuit to supervisory lamp AS is closed by way of spring 125, spring 123, the winding of relay 114 to battery. Relay 114 energizes to close the circuit to the supervisory pilot lamp SP. 70 The operator, noting the supervisory lights, takes down the connection, restoring all equipment to normal in readiness for the next call,

In the event of the station A¹ calling the 75 station A⁴, the ringing control relay 108 is locked up over a circuit including springs 139, 137, 127 and 120 and the break contact of the latter to ground. If the called party fails to respond, the calling party hangs up 80 and operates the generator to transmit a disconnect signal. Thereby operating the relay 101, which closes the circuit of the supervisory lamp AS over the springs 126, to the supervisory pilot FSP, causing the 85 supervisory lamp AF to be flashed as before described. The relay 101, at spring 127, interrupts the locking circuit of relay 108, causing that relay to deenergize and to disconnect the ringing current from the 90 called line. The operator supervises the call and takes down the connection as previously explained.

From the foregoing description it will be 95 evident that I have designed new and useful supervision features for magneto lines. While I have chosen to illustrate my invention in connection with a particular type of equipment, I have done so merely by way of example, as there are many modifications 100 which can be made by one skilled in the art, without departing from the scope of the invention.

What I consider new and desire to have 105 protected by Letters Patent is pointed out in the appended claims.

What is claimed is:

1. In a telephone system, a magneto subscriber's line, a common battery subscriber's line, a cord circuit containing an answering supervisory signal and a calling supervisory signal, means for initiating a call from said magneto line, means for connecting said cord circuit to said calling line and for extending the connection to said common battery line as a called line, means for automatically projecting ringing current on said called line, and means controlled by said calling subscriber for disconnecting said ringing current.

2. In a telephone system, a magneto subscriber's line, a common battery subscriber's line, a cord circuit containing an answering supervisory signal and a calling supervisory signal, means for initiating a call from said magneto line, means for connecting said cord circuit to said calling line and for extending the connection to said common battery line as a called line, means for automatically projecting ringing current on said called line,

and means controlled by said calling subscriber for disconnecting said ringing current and for flashing said answering supervisory signal.

- 5 3. In a magneto telephone system, subscribers' lines, magnetos on said lines, cord circuits including supervisory signals and line relays, said line relays being normally connected in bridge of the talking conductors of said cord circuits and adapted to be operated by said magneto lines, means for connecting said cord circuits to said lines, and a pair of relays operated alternately responsive to the operation of said line relays by 10 said magneto lines for intermittently operating said supervisory signals.
- 15 4. In a magneto telephone system, subscribers' lines, magnetos on said lines, cord circuits including supervisory signals and line relays, said line relays being normally connected in bridge of the talking conductors of said cord circuits and adapted to be operated by said magneto lines, means for connecting said cord circuits to said lines, mechanical means for locking said line relays 20 in their operated positions, a pair of relays operated responsive to the operation of said line relays by said magneto lines for intermittently operating said supervisory signals,

and means to release said line relays from 30 their operated positions to stop the operation of said signals.

5. In a telephone system, subscribers' lines of two types, a universal cord circuit containing signals, means for connecting said cord circuit with said lines, a single relay means for adapting the cord circuit to the type of line with which it is being used, and double relay means for intermittently operating said signals when the cord is being 35 used with one of said types of lines.

6. In a telephone system, subscribers' lines of two types, a universal cord circuit containing a plurality of signals and a line relay, means for connecting said cord circuit with said lines, a single relay means for adapting said cord circuit to the type of line with which it is being used, means to energize said line relay when said cord is being used with one of the types of said 40 lines, mechanical means to lock said line relay energized, and a double relay means operating responsive to the energization of said line relay for intermittently operating said signals simultaneously. 45

In witness whereof, I hereunto subscribe my name this 16th day of June, A. D., 1925.

AUGUST W. STEINKE.
